UNITED STATES PATENT OFFICE.

HOLLIS B. CHILDRESS, OF GRANITE, OKLAHOMA TERRITORY.

PIPE GRAPPLE OR PULLER.

No. 823,667.

Specification of Letters Patent.

Patented June 19, 1906.

Application filed July 7, 1905. Serial No. 268,608.

To all whom it may concern.

Be it known that I, HOLLIS B. CHILDRESS, a citizen of the United States of America, residing at Granite, in the county of Greer and 5 Territory of Oklahoma, have invented new and useful Improvements in Pipe Grapples or Pullers, of which the following is a specification.

My invention relates to a device for pulling 10 stakes, pipes, or casings from their fixed or set positions.

One object of this invention is to provide a novel and highly-useful device of this character which will be cheap of manufacture, simple in construction, durable, and efficient.

Another object is to provide a means of this sort having gripping-jaws employed which are concave on their inner sides, said curvatures being provided with a roughened 20 surface or corrugations which will securely hold the pipe or casing when applied.

A further object is to provide gripping-jaws pivotally attached to sliding pieces which are capable of adjustment toward or 25 from each other whereby they may be readily fitted to any size pipe or casing used in plumbing.

A still further object is to provide gripping-bars which by their shape will resume a released position as soon as the pull is lessened and which when equipped with block and tackle will serve as a means for uplifting a 30 pipe, stake, or casing by a series of repeated operations.

35 The invention consists in the construction, combination, and arrangement of parts, more fully hereinafter described, claimed, and illustrated in the accompanying drawings, which disclose the principles of my invention, and 40 in which—

Figure 1 is a side elevation of the device. Fig. 2 is a longitudinal cross-section of the same. Fig. 3 is an enlarged view of one of the sliding pieces with one of the gripping-jaws pivoted thereto.

45 Referring to the drawings by reference-numerals, similar numerals designate similar parts in the different figures.

1 designates a strong metallic frame having on both its sides outwardly-bulging portions 2, adapted to conform to the curvature of the stake, pipe, or casing to which it is applied. Said sides of frame are also provided with four longitudinal slots (designated in 50 the drawings by numeral 3) located at the four plane surfaces between the bulgings and

the ends of the frame. Within these longitudinal slots slide the bearings 4, on which pivot the gripping-arms 5 and sliding pieces 9, which are by means of these slots capable 60 of being adjusted toward or from each other, whereby they may be readily fitted to any size pipe or casing, said adjustment being regulated and made secure by set-screws, (designated by numeral 6.)

65 The gripping-bars 5 have their lower portions cut away on either side, as shown by numeral 7, which permits them to move freely in the recessed portions 8 of the sliding pieces 9. Cutting away the lower sides of gripping-bars 5 forms on said gripping-bars shoulders (designated by numeral 10) which serve as lugs against the upper edges of the frame and prevent the gripping-bars 5 from falling too far to the sides. Above these shoulders and 70 for nearly their entire length the gripping-bars 5 have their inner sides of concave formation on which I have made corrugations or teeth 11, which slant upward, said teeth or corrugations being designed to act as a grip 75 or preventive to the possible slipping of the pipe or stake while it is being pulled from its position.

I have stated in the preceding part of this specification that my invention is to be 80 equipped with block-and-tackle apparatus; but I do not care to limit myself to that specific aid, as the structure of my invention is such that it can be as usefully applied in conjunction with a lifting-jack for such purposes as pulling tent stay-pegs and the like 85 from the ground.

From the foregoing description, taken in connection with the accompanying drawings, the construction and means of operation of 90 the invention will be understood without a further extended description.

Changes in the form, proportions, and minor details of construction may be made within the scope of the invention without departing from or sacrificing any of its advantages.

Having thus described my invention, I claim as new and desire to secure by Letters Patent—

105 1. A grapple comprising a frame, fulcrum-blocks adjustably mounted within the frame, arms pivotally mounted on said fulcrum-blocks, and means whereby the fulcrum-blocks may be relatively adjusted.

110 2. A grapple comprising a frame provided with an elongated opening, an arm having its

pivot-pin adjustably mounted within said opening, a member carried by said pivot-pin, and means engaging said member whereby to adjust the pivot of said arm.

5 3. In the combination of a frame, grapple-arms having concaved active faces and provided with shoulders, sliding mounts for adjusting the said grapple-arms and adapted to

engage their shoulders and prevent the arms from falling too far to the sides. 10

In testimony whereof I affix my signature in presence of two witnesses.

HOLLIS B. CHILDRESS.
